EDWARD REYNOLDS, OF WINNECONNE, WISCONSIN.

Letters Patent No. 88,983, dated April 13, 1869.

IMPROVEMENT IN CHURN-LID SCREEN.

The Schedule referred to in these Letters Patent and making part of the same.

To all whom it may concern:

Be it known that I, EDWARD REYNOLDS, of Winneconne, in the county of Winnebago, and State of Wisconsin, have invented certain new and useful Improvements in Churns; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to churns, and consists in an attachment for the ordinary dasher-churn, to prevent the accumulation of butter or cream on top of the lid.

The drawings show a perspective view of a churn-lid and the dasher handle, with my device applied.

The device consists of a ring, C, of such size as to permit the dasher-handle B to pass readily through it, and which is secured below the lid inside of the churn, as clearly shown in the drawing.

The ring is secured in place by means of arms, a, formed on its outer side, and which are turned up at right angles, and driven into the under side of the lid A. When thus applied, the ring C serves the twofold

purpose of guiding the dasher-handle, and of scraping off from it all adhering cream, butter, &c., which falls back instead of being carried up and deposited outside.

The hole, or opening D in the lid, through which the handle passes, I also make of larger size than usual, and also of increasing size from the inner side toward the outer, so that if any cream should escape to the top it will flow back through this opening.

It is obvious that the ring may be located at any suitable distance below the lid A, from one-half to three-quarters of an inch therefrom being found in practice the most effective.

The ring may be constructed of any suitable material, and may be either round, square, or other form, in cross-section.

Having thus described my invention,

What I claim, is—

The ring C, constructed and arranged in relation to the lid and dasher of a churn, substantially as herein described.

EDWARD REYNOLDS.
